UNITED STATES PATENT OFFICE.

GREGOR GULICH, OF NEW YORK, N. Y.

FIRE-ESCAPE OR LIFE-SAVING TOWER.

1,348,872.

Specification of Letters Patent. Patented Aug. 10, 1920.

Application filed July 21, 1919. Serial No. 312,287.

To all whom it may concern:

Be it known that I, GREGOR GULICH, a citizen of the United States, and a resident of New York, in the county of Kings and State 5 of New York, have invented certain new and useful Improvements in Fire-Escapes or Life-Saving Towers, of which the following is a specification.

The present invention relates to improvements in fire-escapes, and more particularly to devices of this type which are portable.

The main object of the invention is to provide a fire-escape, mounted upon a truck and in the form of a collapsible tower, having 15 platforms which are adapted to be extended to the windows of a building, thereby enabling persons to escape from the latter.

Another object of the invention is to so construct a fire-escape that it may be conveniently extended to any desired height 20 and also readily collapsed for transportation.

A further object of the invention is to so construct the fire-escape that it serves at the 25 same time as a fire-fighting apparatus, it being provided with a plurality of fire hose, each made of as many sections as there are sections provided in the collapsible tower.

A still further object of the invention is 30 to provide a device of the character described, which is simple in construction, efficient in operation, and which can be conveniently put in place, when needed.

With these and other objects in view, 35 which will more fully appear as the nature of the invention is better understood, the same consists in the combination, arrangement and construction of parts hereinafter described, pointed out in the appended 40 claim and illustrated in the accompanying drawings, it being understood that many changes may be made in the size and proportion of the several parts and details of construction within the scope of the 45 appended claim without departing from the spirit or sacrificing any of the advantages of the invention.

One of the many possible embodiments of 50 the invention is illustrated in the accompanying drawings, in which:

Figure 1 is a side elevation of a fire-escape constructed in accordance with the present invention, the same being shown in its extended position; Fig. 2 is a section taken on line 2—2 of Fig. 1, showing mainly the several sections of the fire escape, parts of the

actuating apparatus being omitted so as not to obscure the drawing; Fig. 3 is a horizontal section, on a larger scale, taken through the truck portion of the fire escape, showing 60 the actuating mechanism; Fig. 4 is a section taken on line 4—4 of Fig. 3; Fig. 5 is a section taken on line 5—5 of Fig. 3; Fig. 6 is a vertical section taken through the innermost and the next one in the series of the telescoping sections of the tower, showing one 65 of the platforms in its extended position and the other one in its folded position; Fig. 7 is a section taken on line 7—7 of Fig. 6; Fig. 8 is a side elevation, partly in section, 70 of a mechanism for holding adjoining telescoping tower sections in their extended positions; and Fig. 9 is a horizontal section of the tower with its sections in telescoped positions.

In the drawings, the numeral 10 indicates a truck of any suitable construction, preferably a self-propelled vehicle. The body 11 of this truck is of the usual box-shape, containing the machinery for extending and 80 also collapsing the telescoping sections of the tower of the fire-escape, as will herein-after appear. It houses also a plurality of reels 11', on which are wound fire-hose, for use from the street level. To the top of the 85 body 11 is fixed the outermost section 12 of the tower, also, preferably, box-shaped and provided in its walls with window-openings 13, to admit light and air. Access may be had to the fixed section 12 by means of a 90 ladder 14, that is mounted upon the truck body 11 and leads from the ground to the section 12. Into the tower section 12 are adapted to telescope the movable sections of the tower, denoted in their order by the 95 numerals 15, 16, 17 and 18. Each of these sections is box-shaped, being closed at its lower end by a bottom 19, but open at its upper end, so as to receive the next section in the series. Each of the movable sections 100 is provided with window-openings 20, for the well-known purpose.

To each movable tower section are attached four cables 21, which extend over sheaves 22, the latter being mounted on the 105 next outer section in the series. These cables are fixed to the movable sections adjacent their bottoms, and lead down to drums 23, that are disposed within the truck body 11. With each movable section there 110 are associated four drums. All of these drums are rotatably mounted on four shafts

24, which are journaled in bearings 25, rising from base plates 26. The sheaves 22 are disposed in the four corners of the tower sections, so that an even pull may be exerted on the movable sections, in raising the same. The four shafts 24 are disposed in two groups, one in the front portion of the truck body 11 and one in the rear portion thereof, the shafts of each group being disposed parallel to each other and in alignment with the respective shafts of the other group, as clearly appears from Fig. 3 of the drawings. The four drums nearest to the transverse center line of the truck body 11 are associated with the section 18 of the tower, so that, when these four drums are turned simultaneously in the proper directions, the section 18 will be raised in relation to the section 17. The next four drums are associated with the next section of the series, and so on. To each drum is fixed a gear 27, the two gears on the two front drums of a given tower section being in alignment, and so also the two gears of the rear drums of the said section. Parallel with the shafts 24 and between the two groups thereof is disposed a shaft 28, suitably journaled in bearings 29, that rise from the base plates 26. This last-mentioned shaft is provided with two longitudinal key-ways 30, in which are seated keys 31 on two gears 32, that are adapted to mesh with the gears 27 above mentioned. The shaft 28 receives motion from the engine of the truck, it being provided for this purpose, for instance, with a gear 33, that is adapted to mesh with a gear 34 on a shaft 35, the latter being suitably connected with the engine shaft. The gear 34 is shiftable upon the shaft 35, and thus adapted to be brought into and out of mesh with the gear 33. With the gears 32 is associated a shifting mechanism, comprising, for instance, a pinion 36, meshing with toothed racks 37, upon which are mounted fork-shaped members 38, the latter being in engagement with the gears 32. The racks are shiftable in guides 39 parallel to and in the direction of the longitudinal axis of the shaft 28, and so arranged in relation to the pinion 36 that, in turning the latter, the racks are shifted in opposite directions. In this manner the gears 32 are adapted to be simultaneously engaged with or disengaged from, as the case may be, the four gears 27 of a given set of drums 23.

In order to hold the telescoping tower sections in their extended positions, there are associated with each movable section four dogs 40, arranged in pairs, said dogs being pivoted at 41 adjacent the lower ends of the said sections and carrying at their free ends rollers 42. These rollers are adapted to enter recesses 43 in the top of the next section in the series. Each set of

dogs is connected to an actuating lever 44, that is pivoted at 45 to the bottom of the respective movable tower section. To the actuating lever 44 is fixed a gear segment 46, in mesh with a segment 47, the latter being pivoted at 48 to one of the walls of the respective movable tower sections. To the segment 47 are fixed oppositely extending arms 49, connected by links 50 with the dogs 40. When the actuating lever 44 is shifted in one direction, the two dogs 40, associated therewith, are simultaneously seated in the recesses 43 of the next section in the series, and when shifted in the other direction they are unseated therefrom.

To the tower section 18 are hinged two platforms 51, more particularly to the longitudinal side walls thereof. Each of these platforms is made of a plurality of sections, denoted in their order by the numerals 52, 53 and 54. These sections are adapted to slide one into another, the section 52 being hinged to the respective side wall of the tower, the entire platform, when collapsed and turned around its hinges into vertical position, closing a door opening 55 in the said wall. Each platform section is provided along its longitudinal edges with railings 56, which are adapted to be folded onto the respective platform section, they being held in their extended positions by suitable locking means 57. In order to hold each platform safely in its extended position, cables 58 are attached to each section thereof, said cables running over sheaves 59 to rollers 60, the latter being suitably mounted in the walls of the tower section 18. These rollers are made in the form of curtain rollers, in that they are provided with winding-up springs. These springs are not shown, as they do not form part of the present invention. When the platform sections are extended, the springs are put under tension, winding up the cables when the platform sections are slid one within the other and swung around the hinge into vertical position.

For collapsing the platform, there is fixed to the section 54 thereof a cable 61, the other end of which is secured to a drum 62 within the tower section 18. By winding this cable upon the said drum, first the section 54 slides into the section 53, and then both sections into the section 52.

In order to extend the platform, a cable 63 is attached at 64 to the section 54, and at 65 to the section 53. This cable is also fixed to a drum 66, the latter being disposed within the tower section 18. When the cable 63 is wound upon the drum 66, it causes the sections 54 and 53 to move out of the platform section 52.

The fire hose on the reels 11' in the truck body 11 may be connected with fire hose, that lead to the top section 18, when the

tower is in its extended position. For this purpose there are hose couplings 67 provided in the bottom of each movable section, more particularly in the four corners thereof, which are adapted to be connected by hose sections 68. Hose sections 69 lead from the tower section 18, and to these sections are attached the usual nozzles.

In order to permit the ascent to and descent from the movable tower sections, when the latter are in their extended positions, there are fixed to the tower sections 12 and 15 to 17, inclusive, ladders 70. These ladders are attached to the bottoms of the said sections and lead each to an opening 71 in the bottom of the next section in the series. The ladders are staggered and decrease in width from the section 17 to the section 12, thereby permitting the ladders to be nested when the tower sections are telescoped, as clearly appears from Fig. 9 of the drawings.

The operation of the fire-escape is as follows:—In the telescoped and folded normal positions of the elements, the movable tower sections are within the stationary section 12, the platform sections on the innermost tower section being disposed one within another and shifted around into vertical positions, in which they close the door openings 55. The size of the truck, with the exception of its height, is thus in no way enlarged, so that it can be drawn through the streets without interfering with the traffic.

When the fire-escape is to be put to use, it is brought, adjacent the curb, in parallel relation to the burning building. In order to extend the tower, first the pinion 36 is rotated in the proper direction so as to bring the gears 32 on the shaft 28 in mesh with the gears 27 on those drums which are disposed nearest to the transverse center line of the truck body 11. Rotation is then imparted to the shaft 28 by bringing the gear 34 on the shaft 35 into mesh with the gear 33 on the shaft 28. In this manner the innermost tower section, denoted by the numeral 18, is raised. When fully raised, its dogs 40 are brought in alinement with the recesses 43 in the tower section 17. The respective actuating levers 44 are then shifted in the proper direction, so as to engage the dogs with the said recesses. The section 17 is then raised by engaging the gears 32 with the next four drums in the series. It is then fixed in place by its dogs 40. These operations are continued until the tower section 18 is brought to the proper level. When this section is at its proper height, the platform 51, adjacent the building, is brought into horizontal position and the drum 66 turned in the proper direction until the outermost section 54 of

the said platform is brought to rest on a window-frame on the building (Fig. 2). The railings 56 on the platform sections are then brought to their extended positions, whereby a proper bridge is formed, on which persons may leave the burning building and enter the tower section 18, descending on the ladders 70 to the stationary tower section 12, and leaving the latter on the ladder 14. The hose sections 68 are then connected with the hose on the reels 11' in the truck body, and the last-mentioned hose connected to the fire-apparatus. The hose sections 69 are then directed against the burning building, the firemen stepping onto the extended platform or remaining within the tower section 18, as required.

In order to telescope the tower, obviously the operations described for extending the same must be performed in the reverse order. It is obvious that, both in raising and lowering the tower sections, the shaft 28 is disconnected from the shaft 35 every time that the gears 32 are shifted into engagement with or disengaged from a given set of gears 27. A disengagement of the gears 33 and 34 must also take place every time that a tower section is brought to a height in which its dogs 40 register with the recesses 43 in the next section of the series.

From the foregoing it appears that the device herein described constitutes an efficient, combined life-saving apparatus and fire-fighting device.

What I claim is:—

A portable fire-escape comprising a truck, a tower thereon made of a plurality of box-shaped sections, each section being provided with a bottom but open at its upper end, one section of said tower being fixed to said truck and the others being adapted to telescope into said fixed section, means for raising said movable sections in succession in relation to said stationary section, each of said bottoms but that of the outer-most section being provided with an opening, said openings being in alinement, a ladder secured to each movable section but the outer-most section, said ladders being fixed to the respective bottoms of said sections and slanting from the top of the respective section to its bottom in alinement with the opening in the bottom of the next section, said ladders being of different widths and staggered in relation to each other, thereby permitting the same to be nested when said tower is telescoped.

Signed at New York, in the county of New York, and State of New York, this 14th day of July, A. D. 1919.

GREGOR GULICH.
